UNITED STATES PATENT OFFICE.

THEODORE ESKILSSON, OF NEW YORK, N. Y.

AUTOMATIC DOOR-CONTROL DEVICE FOR ELEVATORS.

Application filed June 29, 1926. Serial No. 119,269.

This invention relates to elevators and like structures and more particularly to safety devices for such elevators and like structures, and aims to eliminate the danger accompanying the operation thereof, as by opening the shaftway enclosure doors, when such elevators are not at a certain level with respect to the landings for which service is desired, and as by starting the elevator before the doors of said landings have been properly closed.

It is an object of the invention to provide elevators and like structures with safety devices which are positive in action and automatic in operation; which operate in conjunction with the standard controllers of the elevators and like structures; which are easily installable on any type of elevator and like structure; which require but little space in the elevator cars and on the landing doors of the shaftways; which shall prevent starting the elevators and like structures while the shaftway landing doors are open; which shall prevent opening such door while the elevators are in motion, permitting such opening only when the elevators are stopped at a certain position or level with respect to the landings of such doors; and which shall provide all safety means required by law, both in the operation of the elevators and in the operation of their enclosure doors.

Other objects and advantages of the invention will appear in the specification which is descriptive of an illustrative embodiment of the invention shown in the accompanying drawings, to which illustrative embodiment and the description thereof I do not limit myself since the same may be varied without departing from the spirit of my invention.

Before describing the invention in accordance with the illustrated example, it is believed best to point out briefly some of the dangers and hazards which are present in the operation of elevators and like structures, and which my invention eliminates.

Elevators and like structures depend for their operation upon the human element, that is, on the care and skill of the operators of the elevators who, no matter how careful they may be, are always apt to err and open the shaftway landing enclosure doors, for which service is desired, when the elevators are not brought entirely to a stop or when they are stopped at an off-level with respect to the landings of such enclosure doors.

Many times, when such doors are so opened, injury results to the incoming and outgoing passengers, for they may fall when getting in or out of the elevators, being unaware of the step-up or down which the elevators may present when not at a proper level with respect to the floor of the landings. But the more serious dangers and hazards are those when such operators start the elevators before the landing doors have been properly closed leaving such doors open to afford a drop to unaware persons on the landings who might venture near such open doors and even to persons on the elevators who may attempt to get off the elevators after the same have been started, misled by the open doors. Other dangers afforded by not closing such doors are those of allowing possible fires starting on any floors to find their way into the elevator shaftways through the open doors, to the damage of the cables of the elevators endangering the safety of the same; and also affording a source of communication of flames to the other floors communicating with the shaftways endangering all the floors of the building in which the fire occurs, and which could have been prevented if all the doors of the shaftways are properly closed.

The invention purposed to eliminate all of the above pointed out and all of the other dangers present in the operation of elevators; and also purposed to provide all the means necessary to comply with the regulations and laws imposed by the different municipalities and States, since all of such regulations and laws aim to prevent the dangers above pointed out.

In the accompanying specification I shall describe, and in the annexed drawings show, an illustrative embodiment of the invention; and it is here again pointed out that the invention is not limited to the specific form herein shown and described.

Referring to the drawings herein, in which I have illustrated the aforesaid illustrative embodiment of the invention:

Figure 1 is a side elevational view showing an embodiment of the invention applied to an elevator and associated with the controller of such elevator.

Figure 2 is an enlarged view of a portion of the embodiment shown in Figure 1 and taken on line 2—2 of that figure.

Figure 3 shows a door-locking mechanism associated with each shaftway enclosure door which is engaged by the device carried on

the elevator as shown in Figure 1, the showing being in side elevational view.

Fig. 4 is a transverse sectional view taken on line 4—4 of Fig. 3.

5 Figure 5 is a figure similar to Figure 2 but showing the parts thereof in a different or disengaged position.

10 Figure 6 is a view similar to Figure 3, but showing the parts in the position corresponding to the position shown in Figure 5.

Figure 7 is a view taken on line 7—7 of Fig. 6 showing, more clearly, the top view of the door locking mechanism.

15 Figure 8 shows a portion of a door-locking bar which co-engages with the door locking mechanism.

Figure 9 is a perspective view of a bar and plate which engage with the mechanism carried by the elevator.

20 Figure 10 shows a portion of the elevator controller-box and parts of the device to be hereinafter referred to.

Figure 11 shows a key-locking mechanism employed on each enclosure door.

25 Figure 12 is a sectional view of Figure 11 and taken on line 12—12 in Figure 11.

Figure 13 is a cross-sectional view of a portion of the device taken on line 13—13 in Figure 1.

30 Figure 14 shows a sectional view of a portion of the device taken on line 14—14 in Figure 13.

Figure 15 is a diagrammatical view of the 35 electrical circuit of the illustrative embodiment of the invention.

In the drawings, in the elevator 20 and adjacent the elevator controller 21, I mount the electrical apparatus of my device which will be hereinafter described more in detail.

40 Through the floor 22 of the elevator extends a slidable rod 23 formed at its lower end with a head 24 to which is secured a pin 25'. At the lower face of the elevator floor 22 I secure a bracket 25 formed, intermediate its ends, with a bearing 26, and at its lower end are secured by means of a pivot pin 27 links 28 and 29. Each of these links is formed at its free end with an oblong slot 30; the axis of one of the slots being disposed at an angle to 45 the axis of the other slot. The slot 30 of the link 29 accommodates the pin 25' of the slidable rod 23; and the slot of the link 28 accommodates a pin 31, which pin is secured to one end of a stub shaft 32, which stub shaft is slidably arranged in the bearing 26 of the bracket 25. At the opposite end of the said stub shaft 32 I secure, by any approved means, such as a rivet 33 a plate 34 preferably formed with a hub 35 for accommodating one end of the stub shaft 32. It will here be seen that when the rod 23 is滑ed one way or the other and its sliding movement is transmitted through the links 28 and 29 to the stub shaft 32, and likewise the movement of the stub shaft 32 is transmitted to the slidable rod 23.

50 Adjacent each landing of the shaftway in which the elevator operates, and preferably near the lower end of the shaftway enclosure doors 40, on the wall of the shaftway, I attach in any approved manner a box or casing 70 41 formed in the front face thereof with an opening 42, in which moves a cam plate 43, preferably integral with a bar 44 the lower end of which is pivoted as at 45 to hinge lugs 46 formed in the casing 41. The upper or 75 free end of the bar 44 is formed with an angularly disposed slot 47, in which is actuated a pin 48, the latter being secured to a toothed member 49 which is also pivoted to the casing 41 by means of hinge lugs 50 and 80 pin 51. The toothed member 49, intermediate its ends, is formed with a series of teeth 52, and at its free end is formed with an enlarged portion 53 in the lower end of which is also formed an oval slot 54 disposed at an angle 85 to the longitudinal axis of the toothed member 49. Within the casing 41 and approximately in its center, is pivoted by means of a pin 55 a weight 56, which is so pivoted that it normally moves under its own gravity to one 90 side as shown in Figure 6. Said weight 56, at its upper end, carries a pin 57 which is accommodated in the slot 54 of the toothed member 49, and by means of this weight 56 and the pin 57 the toothed member 49 is always urged to move upwardly. It is, of course, understood that any other means could be employed for urging the toothed member 49 95 upwardly.

On each door 40 I mount, by means of a 100 guide 60 which is secured to the door by screws or other similar devices 61, a slidable locking bar 62 formed at its lower end with a projection 63 which projection is adapted to engage any of the teeth 52 of the toothed member 49. To the said locking bar adjacent the projection 63 is secured, by any approved means such as rivets 64, an L-member 65, one leg of which is disposed substantially at right angles to the longitudinal axis of the locking bar 62 and formed with a tongue portion 66 projecting rearwardly and presenting a curved or cammed face so as to smoothly engage with the upper end of the pivoted bar 44. It will thus be seen that by exerting a 105 pressure on the cam plate 43 the pivoted bar 44 is swung rearwardly and the pin 48 is pulled downwardly, through the medium of the oblong slot 47, and thus disengaging the toothed member 49 from the lock bar 62 to 110 permit an opening of the door 40. See Figures 2, 3 and 4.

I have shown in Figures 2, 3 and 4 the 115 plate 34 in engagement with the cam plate 43, and the pivoted bar 44 disposed substantially vertically at which position the pin 48 together with the toothed member 49 have been moved, to such a position that the teeth 53 are free from the projection 63 of the slide bar 62. But it will be noted in Figure 4 that 120

upon opening the door and moving the tongue portion 66 of the L-member 65 the pivoted bar 44 occupies a position to the right of the longitudinal medial plane of the box 41, and in 5 that position the cam plate 43 has permitted the plate 34 to move further outwardly permitting at the same time, through the medium of the stub shaft 32 and the links 28 and 29, the slideable rod 23 to move further upwardly 10 under the action of a spring 70 as shown in Figure 1 to which a more specific reference is to be had later. It will also be noted that the pivoted bar 44, when the plate 34 pushes against the cam plate 43, moves only to approximately that position shown in Figure 2 15 because the lower leg of the L-member 65 prevents the said pivot bar 44 from moving any further than the position shown in Figure 2; but upon opening the door 40, the lug bar 62 20 together with the L-member 65 is carried away from its normal position and the pivoted bar 44 is permitted, under the pressure of the spring 70, to further move approximately to the position shown in Figure 4.

25 For the purpose of emergency and to comply with the different laws enacted by State and city legislative bodies, the following arrangement is made: The lug bar 62 is connected by means of a rod 75 with a key operated lug mechanism 76, and the rod 75 is guided by a guiding clamp 77 secured in any approved means to the door 40. Said rod 75 is preferably enveloped by a spring 78 which is interposed between a guiding clamp 30 77 and the upper end of the lug bar 62, so that the said lug bar 62 will be constantly urged downwardly. It is, of course, understood that any other means could be used besides the spring or the same could be entirely 35 eliminated because the bar 62, if free of friction, will move downwardly under its own gravity. The lock mechanism 76 is shown in detail in Figures 11 and 12, to which reference is now made; and it comprises a casing 40 45 50 55 60 65 70 75 80 85 88 90 95 100 105 110 115 120 125 130

80, preferably having a removable cover 81 and formed with openings 82 and 83 in the sides thereof. Through the opening 82 passes a rod 84 one end of which is pivotally connected, as at 85, with a manually operated releasing member 86 mounted on the door 40, and the other end of which is guided in a guide clamp 88 secured to the lock casing 80. Said other end of rod 84 is formed with a head 87. Between the guiding clamp 88 and the head 87 is arranged a collar 89, the bore of which is formed with flaring walls 90, as shown in Figure 11, and this collar forms a part of the rockable actuator 91 mounted to rock on the pivot 92; and carrying, substantially at right angles to the collar 89, a second collar 93, the bore of which is also formed with flaring walls 94. The rockable actuator 91 is also formed below the pivot 92 with a cam portion 95, having a cam face 96 which normally bears against the cam face 97 of a key-operated cam 98, having a slot 99 to receive a key or like device passed through a slot in the removable cover 81 of the casing 80. From the description of this arrangement it will be seen that in case of emergency 70 the operator, operating the elevator, may open the door 40 independently of the door-locking mechanism above referred to and actuated by plate 34. Assuming that, for any reasons whatever, the operator desires to 75 open the door 40 independently of the afore-described door-locking mechanism, he inserts a key, which is carried by him, into the slot 99 of the cam actuator 98 and turns that cam into a position substantially at right angles to the position shown in Figure 11 or into a position where the straight portion of the cam face 97 lies substantially parallel with the cam face 96 of the rockable actuating member 91; and then swings the manually 80 actuated releasing member 86 in the direction in which the rod 84 is pulled to the right or toward the manually actuated releasing member 86. The rod 84 in turn, through the medium of head 87, pulls the collar 89 which 90 rocks, on the pivot 92, the rockable actuating member 91 and moves upwardly the collar 93, which in turn pulls upwardly, against the action of the spring 78, the rod 75 and the lock bar 62; thus disengaging the latter from 95 the toothed member 49, even when said member is in its uppermost position. After closing the door the operator moves the releasing member 86 in the opposite direction and places the rockable actuating member 91 in 100 its normal position as shown in Figure 11, and turns the key actuated cam 98 to the position shown in Figure 11 to lock the rockable actuator 91 against movement. When the operator moves the bar 62 downwardly the 105 toothed member 49 is pushed downwardly and thereby the parts of the door lock mechanism are returned to the position shown in Figures 2 and 3.

As a further emergency and to permit the door to be opened from the outside, I arrange at the upper end of the rod 75 a sleeve 105 formed at its upper end with a flange 106, which sleeve passes through or bears against the walls 94 of the collar 93 and is guided at 110 its lower end by means of a guide clamp 107 secured to the inner face of the lock casing 80. The rod 75 carries at its upper end a head 108 formed with an oblong slot 109, which normally registers with a key slot 110 extending to the outer face of the enclosure door 40. The head 108 may be screwed or otherwise secured to the rod 75 and is formed with an annular flange 111 which normally bears against the upper face of the flange 106 of the sleeve 105. Preferably, but not necessarily, a collar 112 is secured by means of a screw or rivet 113 to the sleeve 105 so as to regulate its longitudinal movement of the lock bar 62. From the above-described

tion it will be seen that I may open the door 40 from the landing by inserting a key through the slot 110 and turning the same within the oblong slot 107 in the head 108, causing a pull upwardly on the head 108, the rod 75 and the lug bar 62, to disengage the same from the toothed member 49. It will be noted from the above description, that the door 40, may be opened manually by the operator without the aid of any pressure on the plate 43 or it may be opened from the landing also without the aid of any pressure on the plate 43.

The device for actuating the plate 34 and the mechanism for locking the doors are carried on the elevator as above pointed out, and principally comprising a weight 120, formed with a projection 121, suspended by means of a flexible element or chain 122 from the elevator controller handle 123. Preferably, the flexible element 122 is guided over sheaves 124 and 125 so that the weight 120 may reciprocate up and down when the handle 123 is rocked on its pivot 126. In the immediate vicinity of the weight 120 are arranged electro-magnets 130 and 131, each operating the respective plungers 132 and 133; the plunger 132 being connected with the slidable rod 23, and the plunger 133 being connected with a dog 135 pivoted at 136. The plunger 132 in addition to the slidable rod 23 carries a standard 138, to which is secured a circuit closer 139 operating between the electrical contacts 140 and 141, and which contacts it normally bridges. The dog 135, which is secured to the plunger 133, is formed at its rear end with an eye 145, to which is secured one end of the spring 146 whose opposite end is secured to an eye 147 carried by the frame of the magnet 131. The spring 146 urges the dog 135 in the direction wherein the lower end of the dog 135 occupies a position in the path of movement of the projection 121 on the weight 120, so as to prevent an operation of the controller handle 123 while the magnet 131 is deenergized. The weight 120, when moved in its downmost position, engages one leg 150 of the pivoted circuit breaker 151, which rocks on the pivot 152 and which is formed with a collar 153 below the pivot 152 and with a contact blade 154 above the said pivot. The contact blade 154, when the weight 120 is moved away from its lowermost position, engages or contacts with the contact 155, which contact is the terminal of one of the leads of the coil of the magnet 130. To the frame mounting the magnet 130 or to any other support is secured a guide rod 160, which extends through the bore of the collar 153; and between the collar 153 and the frame mounting the magnet 130 is interposed a spring 161, the latter being adapted to urge the circuit breaker 151 in contact with the terminal 155.

Before describing the operation of the

magnets and their associated parts, a description of the circuit of said magnets will be first entered into. Reference is now had to Figure 15 wherein said circuits are diagrammatically illustrated and which are connected to a source of electrical supply (not shown) by means of conductors 170 and 171. The circuit of magnet 130 comprises a conductor 172, connected to the conductor 171 and connected with one end of the coil of the magnet 130, as at 173. The other end of the coil of the magnet 130 is connected to the terminal 155 as above described which is engaged by the contact blade 154 of the circuit breaker 151, and at a spaced point 70 from the terminal 155, a second terminal 174 is arranged to which is connected the conductor 175, the latter being connected as at 176 to the opposite side of the source of electrical supply to which the conductor 170 extends. Here it will be seen that the current from the source of electrical supply when the blade 154 of the circuit breaker 151 bridges the terminals 155 and 174; passes from the conductor 171 through conductor 172, 85 through the coil of the magnet 130, to the terminal 155, through the blade 154, to the terminal 174 and through the conductor 175, thence back to the conductor 170 which is connected with the source of electrical supply. 95

The circuit of the magnet 131 is the following: Conductor 180 is connected to the conductor 171, and to the contact 141 a second conductor 181 is connected to one end of the coil of the magnet 131 and to the contact 140. 100 To the opposite end of the coil of the magnet 131 is connected a conductor 182, which in turn is connected with the terminal 183 on the switch box 184 of the elevator controller. The terminal 183 is disposed at one side of 105 the longitudinal medial plane of the switch box 184, and on the other side of the said longitudinal medial plane of the box 184 is also arranged another terminal 185 which is connected to the conductor 182 by means of a 110 conductor 186. At spaced points from the terminals 183 and 185 are also arranged, on the switch box of the elevator controller terminals 187 and 188 which, by means of the respective conductors 189 and 190, are connected to the conductor 191 which is connected with the other side of the source of electrical supply or to the conductor 170. The handle 123 of the elevator controller carries a bridging plate 193 which may be insulated from the handle and which is adapted to bridge either the contacts 183 and 187 or the contacts 185 and 188, as the case may be, when the said handle 123 is moved from or to its neutral position to make or break the circuit or circuits to the motor driving the elevator, which circuit or circuits are fractionally indicated by the contacts 195 and conductors 196. A description of the circuit or circuits of the motor driving the elevator 125 130

is not necessary since the standard circuit and controller is used and since the present invention has no bearing on the said circuit or circuits.

5 The operation of the device is as follows: In stopping the elevator the operator moves the handle 123 to its neutral position as shown in Figure 1, and in so doing allows the weight 120 to move downwardly opening the circuit breaker 151, and breaking the circuit of the magnet 130. Assuming that the elevator has been stopped adjacent a shaftway enclosure door for which service is desired and also stopped in that position in which the plate 34 10 is engaged with the cam plate 43; the spring 70 is allowed, since the magnet 130 is now deenergized, to push the plunger 132, together with the slidable rod 23, upwardly, thereby causing the links 28 and 29 to rock on their 15 pivot 27 and push the stub shaft 32 against the cam plate 43, forcing the latter rearwardly until the pivoted bar 44 is stopped from further movement by the L-member 65; and when the L-member 65 is withdrawn 20 from the position shown in Figure 3 the spring 70 is then permitted to further push the cam plate 43 and the rod 44 further rearwardly until the rod 44 occupies the position shown in Figure 4. Incidentally, in so doing, the plunger 132 together with the standard 25 138 and the circuit closer 139 push further upwardly until the said circuit closer 139 is disengaged from the contacts 140 and 141, breaking the circuit of the magnet 131. When 30 the circuit closer 139 does not bridge the contacts 140 and 141, the magnet 131 being deprived of electrical current is deenergized and its plunger 133, under the action of the spring 146, is withdrawn, swinging the dog 135 in 35 the full line position shown in Figure 1, in which position the lower end of the dog 135 is placed in the path of movement of the projection 121 and thereby preventing an operation of the controller handle 123 while the 40 shaftway door is opened, and consequently preventing a starting of the elevator while the said door is open. When the door just opened is closed the rounded face of the tongue 66 of the L-member 65 engages with 45 and forces the pivoted bar 44 in the position shown in Figure 2, thereby projecting the cam plate 43 outwardly and forcing the plate 34 rearwardly, which in turn, through the medium of the stub shaft 32 and the links 28 and 50 29, causes the slidable rod 23 to move downwardly against the action of the spring 70 and in so doing causes the circuit closer 139 to bridge the space between the contacts 140 and 141 and close the circuit of the magnet 131. 55 Here it will be noted, as it appears in Figure 1, that the weight 120, when in its lowermost position prevents the projection 121 at some or noticeable distance from the lower end of the dog 135 so as to permit a slight movement 60 of the handle 123, whereby any one of the sets

of terminals 185 and 188, or 183 and 187 may be bridged by the bridging plate 193 before the dog 135 is moved out of the path of movement of the projection 121, as shown in dotted lines in Figure 1. Assuming that the door is 70 closed and that the circuit closer 139 is now bridging the contact members 140 and 141, and that the operator moves the handle 123 in one direction or the other, upon so doing the circuit of the magnet 131 is closed thereby 75 energizing the said magnet 131 and causing the plunger 133 to move outwardly and rock, on the pivot 136, the dog 135 so as to move away from the projection 121 its lower end and permit the handle 123 to be moved 80 past any set of the contacts 186—188 or 183—187. Attention is here called that the circuit of the magnet 133 is interrupted by the circuit closer 139 and by the bridging plate 193, and that when the circuit closer 85 139 is not bridging the contacts 140 and 141; that is, when the door 40 is open, a movement of the handle 123 in one direction or the other will not close the circuit to the magnet 131 because the same is broken by the circuit 90 closer 139. In order that the circuit of this magnet 131 may be closed, the door 40 must first be closed, otherwise the circuit closer 139 will not bridge the contacts 140 and 141. Therefore when the door 40 is closed and 95 the circuit closer 139 bridges the contacts 140 and 141, current will flow when the blade 193 bridges any of the sets of contacts 183—187, 185—188, in the following manner: From the source of electrical supply, through the conductors 171, 180, contact 141, circuit closer 139, contact 140, through the conductor 181, through the coil of the magnet 131, through the conductor 182, to any one of the contacts 183 or 185, through the bridging plate 193, 100 through any one of the contacts 187, 188 and any one of the conductors 189, 190 through the conductor 191, back to the conductor 170 which is connected to the other side of the 105 source of electrical supply. 110

It is thus seen, from the above description, that through the medium of the apparatus just described it is impossible to open any of the landing doors of the shaftway in which the elevator travels without first stopping the elevator at a certain position with respect to the landing for which service is desired and that it is impossible to start the elevator after the door has been opened without first properly closing that door. The operation of the device is automatic and requires no further manipulation by the operator than is necessary to operate the ordinary elevator controller, unless the operator fails to stop his elevator at a proper level with respect to the landing for which service is desired. 115 120 125

However, it may occur that the apparatus just described may get out of operation and in order not to impede the operation of the 130

said elevator, I have resorted to certain safety devices which will hereafter be described in accordance with the illustrated example.

From the hub 200 of the dog 135 I extend an arm 201 which carries at its free end a knob or handle 202, which is only shown in dotted lines, and which projects through a curved slot 203 in the casing enclosing the apparatus, or possibly through the controller casing. By means of this arm 201 I may swing, manually, the dog 135 and in case the elevator is stopped between landings, or in case the coil of the magnet 131 burns, I may manually swing the dog 135 out of the path of movement of the projection 121 and thereby allow a starting of the elevator independently of the magnet 131. It is understood that this arm is only used for emergency purposes, and only in order to permit the operator to bring his elevator to a landing to let out his passengers or merchandise, after which the apparatus can be repaired.

It may also occur that the winding or coil of the magnet 130 may burn out or it may occur that the circuit breaker 151 gets out of order, and to prevent the elevator from being totally incapacitated while such occurrence has taken place and exists, I associate with the dog 135 a link 204 which is formed with a slot 205 to accommodate a pin 206 fast on the dog 135. The link 204 is pivotally connected, by means of a pin 207, to a crank arm 208 which in turn is rockable on a pivot 209. Integral with the hub of said link 208, and substantially at right angles thereto, I extend an arm 211 which passes through an opening 212 extending transversely through the plunger 132. The outer end of said arm 211 projects through the casing enclosing the magnets or through the casing of the elevator controller and I protect the same by means of an outer box 213 which has a glass front 214, and which is adapted to be broken by a hammer 215 when the operation of the arm 211 is desired. When the glass 214 has been broken and the apparatus is to be rendered inoperative, the arm 211 is pushed downwardly (see Figs. 13 and 14) until the said arm is engaged and held by the lower end of a spring latch 216 in which position it remains until so desired. Hence, upon the apparatus becoming inoperative the glass 214 is broken, the arm is pushed downwardly far enough to be engaged by the lower end of spring 216 which in so doing forces the plunger 132 downwardly, causing the circuit closer 139 to permanently bridge the contacts 140 and 141, and also causing the rod 23 to move downwardly far enough until it has moved the links 28 and 29 to that position in which the plate 34 is withdrawn from operation, as shown in Figure 5, and in which the said plate normally lies when the elevator is travelling.

I would state in conclusion that while the

illustrated example constitute practical embodiments of my invention, I do not limit myself strictly to the exact details herein illustrated, since, manifestly, the same can be considerably varied without departure from the spirit of the invention as defined in the appended claims.

What I claim as my invention is:

1. A safety device for elevators comprising an electro-magnet, a circuit therefor, a pivoted member for closing and opening said circuit, a suspended weight moved up and down by the handle of the elevator controller and adapted to engage said pivoted member to open or close said circuit, means actuated by said electro-magnet, and means associated with the doors of the shaftway landings in which the elevator travels engageable by said first-mentioned means for controlling the operation of said doors. 85

2. A safety device for elevators comprising an electro-magnet, an electrical circuit therefor, a plunger and rod actuated by said magnet, a spring against which said plunger and rod move when the magnet is energized, means connected with said plunger and rod and moved thereby, a second means for controlling the operation of the landing doors of the shaftway of the elevator, and means actuated by the controller handle of the elevator for opening and closing said circuit to affect said magnet and thereby both of said means. 90

3. A safety device for elevators comprising an electro-magnet, an electrical circuit therefor, a circuit interrupter, a weight adapted to engage said interrupter to open the same, a flexible element suspending said weight, sheaves on which said flexible element is guided, a controller handle connected with said flexible element, said flexible element and weight moving up and down as said controller handle is moved, and means actuated by said magnet for controlling the operation of the shaftway landing doors and of the elevator controller. 100

4. A safety device for elevators comprising an electro-magnet, an electrical circuit therefor, a circuit breaker in said circuit, a spring actuated plunger in said magnet, a controller handle, means actuated by said controller handle engageable with said circuit breaker to open the same when the said controller handle is brought toward a certain position, and means actuated by said plunger for controlling the operation of the landing doors of the elevator shaftway and the operation of the elevator after one of said doors has been opened. 115

5. A safety device for elevators comprising a magnet, an electrical circuit therefor, a circuit breaker in said circuit, a plunger actuated by said magnet, a controller detaining member secured to and moved by said plunger, and automatic means for moving said cir- 125

cuit breaker to energize and deenergize said magnet and thereby operate said plunger and controller detaining member.

6. A safety device for elevators comprising a controlling electro-magnet, a circuit therefor, a movable member for making or breaking said circuit, and means associated with said circuit maker and breaker for moving the same out of the circuit when the shaftway 10 enclosure door adjacent which the elevator is stopped is in its open position.

7. A safety device for elevators comprising an electro-magnet, an electrical circuit therefor, means associated with said electro-magnet and actuated thereby for controlling the operation of the elevator controller, a reciprocating element in series with said circuit and means associated with said reciprocating element adapted to be moved in response to 20 the operation of the enclosure doors of the elevator shaftway for moving said reciprocating element out of said circuit when one of said doors is in its open position.

8. A safety device for elevators comprising a pair of electro-magnets, a circuit for each magnet, means operated by the controller handle of the elevator for breaking the circuit to one of said magnets, means actuated by the other magnet to hold said first-mentioned means in a position wherein said circuit is opened, and means actuated by the other magnet to open and close the circuit of the first magnet.

9. A safety device for elevators comprising a pair of magnets, an electrical circuit for each magnet, means carried by the plunger of one magnet to control the circuit of the other, means connected with said plunger for controlling the operation of the shaftway 40 enclosure doors and moving said first-mentioned means to a position breaking the circuit of said other magnet when the door for which service is desired has been opened, and means connected with the plunger of said other magnet to check the movement of the elevator controller while said door is in its open position.

10. A safety device for elevators comprising a pair of electro-magnets, a circuit for each magnet, a weight, a controller handle for moving said weight, a projection on said weight, a pivoted detaining member actuated by one of said magnets and adapted to engage said projection, and means actuated by the other magnet to control the opening of the elevator shaftway enclosure doors, together with the circuit of the first-mentioned magnet to prevent a movement of the controller handle while the door for which service is had is in its open position.

11. A safety device for elevators comprising a pair of electro-magnets, an individual electrical circuit for each magnet, a plunger actuated by each magnet, a spring acting 65 against each plunger to urge the same in

one direction, means connected with one of said plungers for controlling the circuit of the magnet actuating the other plunger, and manually actuated means for controlling the circuit of the magnet actuating said first-mentioned plunger. 70

12. A safety device for elevators comprising a pair of electro-magnets, an electrical circuit for each magnet, a spring-urged plunger actuated by each magnet, means connected with one of said plungers adapted to engage and actuate the locking mechanism of the elevator shaftway's enclosure doors, means carried by one of the plungers for breaking the circuit of the magnet actuating the other plunger for the energizing of the magnet of the last-mentioned plunger when one of said landing doors is opened, manually operated means for breaking the circuit of the magnet actuating said first-mentioned plunger, and means actuated by the other plunger for detaining said manually actuated means in a certain position while the enclosure door is in its open position. 75 80 85

13. A safety device for elevators comprising a pair of electro-magnets, an electrical circuit for each magnet, means associated with the plunger of one magnet to control the circuit of the other, and means actuated by one of said magnets for controlling the operation of the enclosure doors of the shaftway in which the elevator travels. 90 95

14. A safety device for elevators comprising a pair of electro-magnets, an electrical circuit for each magnet, means associated with the plunger of one magnet to control the circuit of the other, and means actuated by one of said magnets for controlling the operation of the enclosure doors of the shaftway in which the elevator travels, together with means actuated by the other magnet for controlling the operation of the elevator controller. 100 105

15. A safety device for elevators comprising a pair of electro-magnets, an electrical circuit for each magnet, a circuit interrupter for each magnet, one of said circuit interrupters being actuated by the plunger of one magnet, means associated with said plunger adapted to engage and operate in conjunction with the locking mechanism of the shaftway enclosure doors in which the elevator travels, the other of said circuit interrupters being actuated by the handle of the elevator controller, and means actuated by the plunger of the other magnet for preventing the operation of said controller handle while the enclosure door adjacent which the elevator is stopped is open. 110 115 120

16. A safety device for elevators comprising a plurality of electrically operated means each provided with means to control the operation of the other, means associated with the enclosure doors of the elevator shaftway adapted to control the operation of said elec- 125 130

trically operated means and of the elevator controller.

17. A safety device for elevators comprising spring-actuated means, electro-magnets actuating said spring-actuated means, means connected with certain of said spring-actuated means for controlling the operation of the elevator controller and means associated with the other spring-actuated means for controlling the lock mechanism of the shaftway enclosure doors and the operation of said first-mentioned spring-actuated means.

18. A safety device for elevators comprising a pair of spring-actuated means, a rod associated with one of said spring-actuated means, a plate connected with said rod, means engageable with said plate for controlling the lock mechanism of the shaftway enclosure doors, magnets for actuating each of said spring-actuated means in opposition to their springs, an electrical circuit for each magnet, means carried by each spring-actuated means for controlling said springs so as to control the operation of said enclosure doors and of the elevator.

19. A safety device for elevators comprising a weight moved up and down by the handle of the elevator controller, a spring-actuated detaining member for preventing the upward movement of said weight when the controller handle has been brought to its neutral position, reciprocating and electrically-actuated means for withdrawing said spring-actuated means from said weight, and means associated with the lock mechanism of the shaftway enclosure doors to operate said reciprocating and electrically-actuated means.

20. A safety device for elevators comprising a spring-actuated reciprocating rod extending through the floor of the elevator, a lock bar associated with each shaftway enclosure door, means engaging the lower edge of said bar to prevent an opening of said doors, a reciprocating plate moved by said reciprocating rod adapted to engage either of said means and to disengage the same from said bar to thereby allow an opening of either of said enclosure doors only when the elevator has been stopped in that position where said plate engages either of said means.

21. A safety device for elevators comprising a reciprocable lock bar associated with each shaftway enclosure door, a pivot toothed member normally engaging said slidable bar to prevent an opening of said doors, spring and electrically-actuated means carried by the elevator and means connected with said pivot toothed member and adapted to co-act with said spring and electrically-actuated means when the elevator has been stopped adjacent either enclosure door, said means being moved by said spring and electrically-actuated means to disengage the slidable bar from the toothed member.

22. A safety device for elevators comprising a reciprocatable lock bar associated with each shaftway enclosure door, a pivot toothed member for each slidable bar and normally engaging the same, said toothed members being adapted to prevent an opening of said doors, spring and electrically-actuated means carried by the elevator, means connected with each of said pivot-toothed members and adapted to co-act with said spring and electrically-actuated means when the elevator has been stopped adjacent either enclosure door, and a dog member actuated by said spring and electrically-actuated means for preventing a starting of the elevator while the enclosure door adjacent which it has been stopped is in its open position.

23. A safety device for elevators comprising a reciprocatable lock bar associated with each shaftway enclosure door, a pivot toothed member for each slidable bar and normally engaging the same, said toothed members being adapted to prevent an opening of said doors, spring and electrically-actuated means carried by the elevator, means connected with each of said pivot toothed members and adapted to co-act with said spring and electrically-actuated means when the elevator has been stopped adjacent either enclosure door, a dog member actuated by said spring and electrically-actuated means, a reciprocating weight moved by the controller handle of the elevator, and means on the reciprocating weight adapted to engage said dog member while the elevator is stopped.

24. In a safety device of the class described, a reciprocating rod projecting through the floor of the elevator, a bracket secured to the floor of said elevator, a stub shaft mounted to reciprocate on said bracket, means between said rod and said stub shaft for transmitting the reciprocation of one to the other, a plate carried by said stub shaft, means arranged with each shaftway enclosure door adapted to be engaged by said plate to release the locking mechanism of said doors.

25. In a safety device of the class described, a reciprocating rod projecting through the floor of the elevator, a bracket secured to the floor of said elevator, a stub shaft mounted to reciprocate on said bracket, means between said rod and said stub shaft for transmitting the reciprocation of one to the other, a plate carried by said stub shaft, means arranged with each shaftway enclosure door adapted to be engaged by said plate to release the locking mechanism of said doors and including a pivot bar, a cam plate carried by said pivot bar and adapted to be engaged by the plate carried by the stub shaft, a rockable bar locking member actuated by said pivot bar, and means on the elevator for reciprocating said stub shaft.

26. A safety device for elevators comprising a slidable rod, a spring for sliding said

- slidable rod in one direction, an electro-magnet for sliding said rod in the opposite direction, a stub shaft arranged at the end face of the elevator floor, links connecting the 5 slide rod with the stub shaft for the transmission of the movement of one to the other, a plate carried by said stub shaft, a door locking mechanism, actuating means for said door locking mechanism, said actuating 10 means being actuated by the reciprocation of said stub shaft and means for preventing a reciprocation of said slide bar and stub shaft when the elevator, while a shaftway enclosure door adjacent which the elevator has 15 been stopped, is open.

27. In a safety device for elevators, a lock bar carried by each shaftway enclosure door, a tongue member secured to the lower end of said bar, a pivot bar engageable by said tongue member when the door is in a certain 20 position, a plate carried by said pivot bar, a toothed member normally engaging said bar to prevent an opening of said door, means connecting said pivot bar with said toothed 25 member to transmit the motion of one to the other and means carried by the elevator adapted to engage said plate for moving said toothed member away from the lock bar to 30 permit an opening of said door.

28. In a safety device for elevators, a lock bar carried by each shaftway enclosure door, a tongue member secured to the lower end of said bar, a pivot bar engageable by said tongue member when the door is in a certain 35 position, a plate carried by said pivot bar, a toothed member normally engaging said bar to prevent an opening of said door, means connecting said pivot bar with said toothed member to transmit the motion of one to the other, means carried by the elevator adapted to 40 engage said plate for moving said toothed member away from the lock bar to permit an opening of said door, and a weight for returning said toothed member in engagement with 45 said bar after the door has been closed.

29. In a safety device for elevators, a bar carried by each shaftway enclosure door, a tongue member secured to the lower end of said bar, a pivot bar engaged by said tongue 50 member when the door is in a certain position, a plate carried by said pivot bar, a toothed member formed with an oblong slot adjacent one end normally engaging said bar to prevent the opening of said door, means connecting said pivot bar with said toothed member to transmit the motion of one to the other, means carried by the elevator adapted to 55 engage said plate for moving said toothed member from the lock bar to permit an opening of said door, a weight element, a pin secured to said weight element and projecting within said slot in the toothed member, said weight being adapted to return said toothed member to its engaging position with the lock bar after the door has been closed.

30. In a safety device for elevators, a bar carried by each shaftway enclosure door, a tongue member secured to the lower end of said bar, a pivot bar engaged by said tongue member when the door is in a certain position, a plate carried by said pivot bar, a toothed member formed with an oblong slot adjacent one end normally engaging said bar to prevent the opening of said door, means connecting said pivot bar with said toothed member to transmit the motion of one to the other, means carried by the elevator adapted to engage said plate for moving said toothed member from the lock bar to permit an opening of said door, a weight element, a pin secured to said weight element and projecting within said slot in the toothed member, said weight being adapted to return said toothed member to its engaging position with the lock bar after the door has been closed, together with manually operated means for moving said lock bar away from said toothed member independently of the lock mechanism.

31. In a safety device for elevators, a bar carried by each shaftway enclosure door, a tongue member secured to the lower end of said bar, a pivot bar engaged by said tongue member when the door is in a certain position, a plate carried by said pivot bar, a toothed member formed with an oblong slot adjacent one end normally engaging said bar to prevent the opening of said door, means connecting said pivot bar with said toothed member to transmit the motion of one to the other, means carried by the elevator adapted to engage said plate for moving said toothed member from the lock bar to permit an opening of said door, a weight element, a pin secured to said weight element and projecting within said slot in the toothed member, said weight being adapted to return said toothed member to its engaging position with the lock bar after the door has been closed, together with manually operated means for moving said lock bar away from said toothed member independently of the lock mechanism, said manually operated means comprising a rod, a pivot member formed with a pair of collars, one of which accommodates one end of said rod and means extended between said lock bar and the other collar of said pivot member for lifting said bar when said rod is reciprocated.

32. In a safety device for elevators, a bar carried by each shaftway enclosure door, a tongue member secured to the lower end of said bar, a pivot bar engaged by said tongue member when the door is in a certain position, a plate carried by said pivot bar, a toothed member formed with an oblong slot adjacent one end normally engaging said bar to prevent the opening of said door, means connecting said pivot bar with said toothed member to transmit the motion of one to the other, means carried by the elevator adapted to engage said plate for moving said toothed member from the lock bar to permit an opening of said door, a weight element, a pin secured to said weight element and projecting within said slot in the toothed member, said weight being adapted to return said toothed member to its engaging position with the lock bar after the door has been closed.

to engage said plate for moving said toothed member from the lock bar to permit an opening of said door, a weight element, a pin secured to said weight element and projecting within said slot in the toothed member, said weight being adapted to return said toothed member to its engaging position with the lock bar after the door has been closed, together with manually operated means for moving 10 said lock bar away from said toothed member independently of the lock mechanism, said manually operated means comprising a rod, a pivot member formed with a pair of collars, one of which accommodates one end of said 15 rod and means extended between said lock bar and the other collar of said pivot member for lifting said bar when said rod is reciprocated, together with a key operated lock mechanism for locking said rod against operation.

33. In a safety device for elevators, a lock bar carried by each shaftway enclosure door, a toothed member normally engaging said lock bar to prevent a lateral movement thereof and of the door, means actuated by the controller of the elevator for disengaging said toothed member from the lock bar, a rod secured to said bar, a spring urging said bar to urge said toothed member, and manually actuated means for moving said lock bar from said toothed member.

34. In a safety device for elevators, a lock bar carried by each shaftway enclosure door, a toothed member normally engaging said lock bar to prevent a lateral movement thereof and of the door, means actuated by the controller of the elevator for disengaging said toothed member from the lock bar, a rod secured to said bar, a spring urging said bar to urge said toothed member, a head formed with a transversal slot secured at the upper end of said rod and manually actuated means insertable in said slot for lifting said rod from the toothed member, and manually actuated means for moving said lock bar from said toothed member.

35. In a safety device for elevators, a lock bar carried by each shaftway enclosure door, a toothed member normally engaging said lock bar to prevent a lateral movement thereof and of the door, means actuated by the controller of the elevator for disengaging said toothed member from the lock bar, a rod secured to said bar, a spring urging said bar to urge said toothed member, a sleeve member formed with an annular flange at its upper end slidably enveloping the upper end of said rod and manually operated means for engaging said annular flange of the sleeve and lifting said sleeve and rod so as to disengage said rod from the toothed member.

36. In a safety device of the character described, a pair of electro-magnets, a plunger actuated by each electro-magnet, a rod se-

cured to one of the said plungers, means associated with said rod for effecting the operation of the shaftway door locking mechanism, and manually actuated means for operating said last-mentioned plunger independently of its magnet.

37. In a safety device of the character described, a pair of electro-magnets, a plunger actuated by each magnet, means moved by the controller handle of the elevator, a dog member actuated by one of said magnets for preventing a movement of said means when the elevator is stopped, a rod secured to the other plunger, means associated with said rod adapted to effect the operation of the shaftway door locking mechanism, and manually actuated means for moving said rod and dog member independently of said magnets.

38. In a safety device of the character described, a pair of electro-magnets, a plunger actuated by each magnet, means moved by the controller handle of the elevator, a dog member actuated by one of said magnets for preventing a movement of said means when the elevator is stopped, a rod secured to the other plunger, means associated with said rod adapted to effect the operation of the shaftway door locking mechanism, and manually actuated means for moving said rod and dog member independently of said magnets, together with a latch for holding said manually operated means in a position wherein said dog member does not engage said means moved by the controller handle.

39. A safety device for elevators comprising a door locking mechanism, means actuating said door locking mechanism for permitting an opening of the doors, an actuating device carried by the elevator and comprising a slidable rod, a slidable stub shaft moved by the rod, a plate carried by said stub shaft for engaging and actuating said means actuating the door locking mechanism, an electro-magnet, a plunger thereon, said plunger being connected with said slidable rod, a spring urging said slidable rod in one direction so as to urge said plunger upwardly of said magnet when the same is deenergized, a second magnet, means carried by the plunger of the first magnet for breaking the circuit of the second magnet, a detaining dog actuated by the second magnet, a spring urging said detaining dog in one direction, a controller handle and a weight associated with said controller handle and moved thereby, said weight being prevented from moving from its lowermost position when the circuit of the second mentioned magnet is open.

40. A safety device for elevators comprising a door locking mechanism, means actuating said door locking mechanism for permitting an opening of the doors, an actuating device carried by the elevator and comprising a slidable rod, a slidable stub shaft moved by

the rod, a plate carried by said stub shaft for engaging and actuating said means actuating the door locking mechanism, an electro-magnet, a plunger thereon, said plunger being connected with said slidable rod, a spring urging said slidable rod in one direction so as to urge said plunger upwardly of said magnet when the same is deenergized, a second magnet, means carried by the plunger of the first magnet for breaking the circuit of the second magnet, a detaining dog actuated by the second magnet, a spring urging said detaining dog in one direction, a controller handle and a weight associated with said controller handle and moved thereby, said weight being prevented from moving from its lower-most position when the circuit of the second mentioned magnet is open, together with a circuit breaker for the first mentioned magnet opened and closed by said weight and adapted to deenergize said first mentioned magnet while a shaftway enclosure door adjacent which the elevator is stopped is open.

41. A safety device for elevators comprising a door locking mechanism, means actuating said door locking mechanism for permitting an opening of the doors, an actuating device carried by the elevator and comprising a slidable rod, a slidable stub shaft moved by the rod, a plate carried by said stub shaft for engaging and actuating said means actuating the door locking mechanism, an electro-magnet, a plunger thereon, said plunger being connected with said slidable rod, a spring urging said slidable rod in one direction so as to urge said plunger upwardly of said magnet when the same is deenergized, a second magnet, means carried by the plunger of the first magnet for breaking the circuit of the second magnet, a detaining dog actuated by the second magnet, a spring urging said detaining dog in one direction, a controller handle and a weight associated with said controller handle and moved thereby, said weight being prevented from moving from its lower-most position when the circuit of the second mentioned magnet is open, together with manually actuated means for moving said plunger of the first mentioned magnet and said detaining dog independently of the magnets.

42. A safety device for elevators comprising a toothed member arranged adjacent the lower end of each shaftway enclosure door, a slidable bar carried by each door and adapted to engage the respective tooth member and means for moving either the toothed member away from the slidable bar or the slidable bar

away from the toothed member for permitting an opening of said door.

60

43. A safety device for elevators comprising a toothed member arranged adjacent the lower end of each shaftway enclosure door, a slidable bar carried by each door and adapted to engage the respective tooth member, key operated means for sliding said bars away from said toothed members so as to permit an opening of said doors.

65

44. A safety device for elevators comprising a toothed member arranged adjacent the lower end of each shaftway enclosure door, a slidable bar carried by each door and adapted to engage the respective tooth members and means actuated by the controller handle of the elevator for moving either of said toothed members away from their respective slidable doors so as to permit an opening of either enclosure door.

70

45. A safety device for elevators comprising a slidable bar projecting through the floor of the elevator, means for horizontally moving a plate carried by the elevator when said slidable bar is moved, a door locking mechanism associated with each shaftway enclosure door, means connected with each of said door locking mechanisms for engaging said plate, and means for manually sliding said slidable bar, said means comprising an arm extending through the opening formed in said slidable rod and means connected with said arm for controlling the operation of the elevator controller while said arm is moved to a certain position.

80

46. A safety device for elevators comprising a slidable bar projecting through the floor of the elevator, means for horizontally moving a plate carried by the elevator when said slidable bar is moved, a door locking mechanism associated with each shaftway enclosure door, means connected with each of said door locking mechanisms for engaging said plate, and means for manually sliding said slidable bar, said means comprising an arm extending through the opening formed in said slidable rod and means connected with said arm for controlling the operation of the elevator controller while said arm is moved to a certain position, together with a second arm associated with said last mentioned means for operating the same independently of said first mentioned arm.

85

In testimony whereof, I have signed my name to this specification this 25th day of June, 1926.

THEODORE ESKILSSON.
